UNITED STATES PATENT OFFICE.

WALTER SHAW, OF BOSTON, MASSACHUSETTS, ASSIGNOR TO UNITED SHOE MACHINERY COMPANY, OF PATERSON, NEW JERSEY, A CORPORATION OF NEW JERSEY.

VENTILATED SHOE.

No. 908,507.

Specification of Letters Patent.

Patented Jan. 5, 1909.

Application filed January 7, 1908. Serial No. 409,653.

To all whom it may concern:

Be it known that I, WALTER SHAW, a citizen of the United States, residing at Boston, in the county of Suffolk and Commonwealth of Massachusetts, have invented certain Improvements in Ventilated Shoes, of which the following description, in connection with the accompanying drawing, is a specification.

This invention relates to ventilated foot-wear and is intended to provide a ventilated shoe which shall be economical in construction, ornamental in appearance and have other advantages hereinafter pointed out.

In ventilated shoes as heretofore constructed the pumping action of the foot in walking was required to draw air from the exterior through long passages, conduits, tubes and the like into the interior of the shoe and to expel the heated air from the interior through the same or similar passages. These conduits were frequently between the upper and its lining or in the sole of the shoe, and they were necessarily expensive, cumbersome and weighty contrivances and had to be built into the shoe in the process of its manufacture. Any system of ventilation depending solely upon the pumping action of the foot was of course useless as a ventilating means while the foot was at rest, or when the shoe was not being worn. All such prior ventilating means failed to produce a ventilated shoe satisfactory to the public in price, appearance, weight, or efficiency, and the use of such shoes has never become general but has been limited to special orders and hence to a comparatively small trade. Furthermore such shoes were found to fail in a most important particular, namely in conveying proper ventilation into the interior of the toe portion of the shoe where ventilation is most needed and where the action of the foot in walking or running and the consequent heat is greatest.

This invention is intended to overcome the difficulties and objections heretofore incident to the use of a ventilated shoe.

Among the objects of this invention is to provide a ventilated shoe with ventilating means which can be applied to a shoe either during the process of its manufacture or after it is otherwise completed, and at practically no increased cost in either case, to provide ventilating means which shall be effective while the shoe is off the foot as well as while it is being worn, and which shall also be ef-

fective whether the wearer is walking or at rest, and also to provide ventilating means which shall not add to the weight of the shoe and which will not detract from its appearance. These objects are secured in the shoe of this invention by forming in the upper ventilating holes so located that they do not attract attention and do not detract from the appearance of the shoe. These holes are preferably formed in the edge of the toe tip where it is customary to form perforations for the purpose of ornamenting the shoe. So located, the holes are not noticeable and in fact, escape the attention of a casual observer. The holes may extend only through the upper materials without penetrating the lining, but preferably they will extend entirely through both the upper materials and the lining, thus affording direct and unbroken connection with the interior of the shoe. In the preferred form of the present invention eyelets are set in the ventilating holes, thus ornamenting the shoe and securing other advantages which will be herein-after pointed out. One of the advantages secured by inserting eyelets in the ventilating holes is the strengthening of the tip seam. In shoes as at present constructed the toe tip frequently breaks away from the vamp, although the seam uniting the toe tip and vamp is usually formed with a double row of stitching. The greatest strain upon the upper during the wearing of the shoe is exerted at the tip seam, as is well-known, and such strain is particularly severe upon a shoe having a box toe.

A further object of this invention is to preserve the box toes of shoes, particularly in the case of patent or enamel leather shoes. Patent leather is so prepared that it is rendered substantially air proof, and it is particularly difficult to dry out that portion of the shoe covered by the box. It has been found by experience that the moisture ordinarily remaining in the interior toe portion adjacent to the box toes tends to rot even the best built boxes causing them to break down because the box absorbs the moisture so remaining in the toe portion after the shoe is removed from the foot of the wearer. This fault is common both to the ordinary old style ventilated shoe and to the non-ventilated shoe.

It is an important feature of the ventilated shoe herein shown to provide for quickly

2
drying up the moisture in the interior toe portion, especially of patent leather shoes, by suitable means of ventilation adjacent to the box. Such means of ventilation does not require a current or flow of air to be forced through, as in the case of long passages or tubes, but enables the exterior air to commingle with the interior and thus to absorb quickly any moisture which may be in the shoe.

10 In the accompanying drawings Figure 1 is a perspective view of a low cut or Oxford shoe embodying a preferred form of the invention, wherein—

15 1 designates the shoe, 2 the vamp, 3 the toe tip or the box toe, and 4 and 5 the usual rows of stitching forming the tip seam.

It is usual to ornament the tip by numerous perforations, such as 13, in the marginal portion of the tip and this invention as herein shown comprises a shoe having ventilating holes in place of some or all of said ornamental perforations. Preferably these ventilating holes extend entirely through the materials composing the upper and the lining. It is also deemed preferable, as shown in the drawing, to set eyelets 6, 7, 8, 9, 10, 11 and 12 in the ventilating holes. Thus ventilation is provided directly to the interior toe portion of the shoe adjacent to the box and such means of ventilation are effective whether the shoe is upon the foot of the wearer or not. The air passages are so short and direct that ventilation is constantly maintained, affording comfort to the wearer and relief from perspiring feet, and furthermore serving to dry up the moisture in the shoe quickly when the shoe is removed from the foot and thus preserving the box from breaking down. It will be readily seen that these ventilating holes are practically invisible taking the place of similar perforations usually formed in the outer layer of the tip. While ventilation through the holes may be increased by the action of the foot within the shoe during walking or running, such action is not essential to secure the advantages of this invention. When eyelets are set in the ventilating holes, as is preferable, they also prevent the tip seam from breaking and by using ornamental eyelets of appropriate size the attractive appearance of the shoe may be greatly increased.

55 This ventilated shoe offers a decided advantage to the retail shoe merchant, as shoes can be conveniently equipped with this means of ventilation upon the order of a customer and after the shoes have been fitted and sold. Hence the retailer need not 60 carry an expensive stock of high priced, slow selling shoes to meet the demand for venti-

lated footwear but is enabled by this invention to supply that demand from shoes ordinarily carried in stock. It also obviates the troublesome and unsatisfactory method of ordering specially made ventilated shoes which often do not fit after they are made and when tried on by the customer.

One of the many objections to ventilated shoes is that rain and moisture are apt to 70 penetrate the ventilating means in wet weather. It will be noted that an advantage of the ventilated shoe herein shown is that the ventilating means are positioned where they may be effectually covered and 75 protected by the ordinary rubber overshoe, and they in no wise interfere with the use of overshoes.

Having described my invention, what I claim as new and desire to secure by Letters 80 Patent of the United States is:—

1. A shoe having a plurality of ventilating holes extending entirely through the materials of the toe tip, vamp and lining and having eyelets set in said holes. 85

2. A ventilated shoe, having a plurality of ventilating holes at the junction of the vamp and toe tip and having eyelets set in said holes.

3. A shoe having a series of ventilating 90 holes across the tip seam between the parallel rows of stitching which secures said seam and having eyelets set in said holes.

4. A shoe provided with a plurality of eyelets at the tip seam as securing means for the 95 vamp and toe portions of the shoe upper.

5. A shoe having a toe tip provided with the usual ornamental perforations in the marginal edge of the tip and having a vamp provided with holes in substantial alinement 100 with the holes in the toe tip whereby ventilation is afforded for the toe portion of the shoe while the appearance of the shoe is substantially unaffected by the provision of the ventilating means. 105

6. A shoe having a toe tip provided with the usual ornamental perforations in the marginal edge of the tip, having a vamp provided with holes in substantial alinement with the holes in the toe tip and having eyelets set in said alining holes whereby ventilation is afforded for the toe portion of the shoe while the appearance of the shoe is substantially unaffected by the provision of said ventilating means. 110

115 In testimony whereof I have signed my name to this specification in the presence of two subscribing witnesses:

WALTER SHAW.
